[57] CLAIM

The ornamental design for a suspended light fixture, as shown and described.

DESCRIPTION

FIG. 1 is a side elevational view of the suspended light fixture according to this invention;

FIG. 2 is a top plan view of the suspended light fixture of FIG. 1;

FIG. 3 is a bottom plan view of the suspended light fixture of FIG. 1; and,

FIG. 4 is a side elevational view of the suspended light fixture of this invention taken from a side opposite FIG. 1.

The light diffusers are shaded with oblique lines to indicate translucency.
